UNITED STATES PATENT OFFICE.

BENJAMIN DOUGLAS THOMAS, OF ITHACA, NEW YORK, ASSIGNOR OF ONE-TENTH TO THOMAS-MORSE AIRCRAFT CORPORATION, OF ITHACA, NEW YORK, A CORPORATION OF NEW YORK.

DRIVING CONNECTIONS FOR AIRPLANE-ENGINES.

1,394,870.

Specification of Letters Patent. Patented Oct. 25, 1921.

Application filed February 28, 1920. Serial No. 361,947.

To all whom it may concern:

Be it known that I, BENJAMIN DOUGLAS THOMAS, a subject of Great Britain, residing at Ithaca, in the county of Tompkins 5 and State of New York, have invented a certain new and useful Improvement in Driving Connections for Airplane-Engines, of which improvement the following is a specification.

10 This invention relates to airplane engines, and has for its object to provide an improved system of driving connections between a plurality of engines and a corresponding number of propellers whereby 15 the efficiency of the power is increased, and a greater degree of safety obtained.

According to my improvement, a plurality of engine units are connected to a plurality of propellers located on a common 20 axis and in close proximity to each other, the adjacent propellers being connected to rotate in opposite directions.

It has been found desirable to place two or more engines in an airplane, in order to 25 increase the power and reliability of the machine, but heretofore the additional engines have been placed in the wings, or one in the front and one in the rear of the center compartment. With the engines in the wings, 30 it is very difficult to fly if one engine fails to function, and the additional weight at these points is also objectionable. It has also been found difficult to mount two or 35 more engines in the center compartment, and have them operate efficiently and independently.

My improvement, however, provides practically two or more power plants, or engines, in one, but each operating wholly independently of the other, or the others, and so arranged that if one of said engines should fail, the others will not be interfered with, but will continue to function, with the result 45 that the airplane will remain in the air, with somewhat diminished power, but will be able to reach its objective and not be forced to land under unfavorable conditions.

In the accompanying drawings: Figure 1 is a plan of one form of airplane power plant 50 embodying my improvement, and showing two six-cylinder engines mounted on a common crank case and each driving a propeller independently of the other; Fig. 2, an end elevation of the same; Fig. 3, a plan, similar

to Fig. 1, but showing three six-cylinder engines driving three propellers; Fig. 4, a side elevation showing two V type engines arranged in tandem; Fig. 5, a plan showing two multi-cylinder V-shaped engines mounted on a common crank case and driving two 60 propellers; Fig. 6, an end elevation of the same; and Figs. 7 and 8, side and end elevations, respectively, showing two multi-radial-cylinder engines arranged in tandem.

Broadly stated, my improvement comprises two or more engines, or power plants, and a corresponding number of propellers located on a common axis, each engine being connected to drive its respective propeller independently of the other.

In Figs. 1 and 2, there are shown two engines, A and B, each having six vertical cylinders arranged parallel and mounted on a common crank case, 15. The crank shaft, 10^b, of engine, B, is provided with a gear 75 wheel, 11^b, meshing with gear, 12^b, on the tubular shaft, 13^b, mounted in suitable bearings in the base, 15, and carrying, at its forward end, the propeller, 14^b. In a similar manner, the crank shaft, 10^a, of the other engine, A, is provided with a gear, 11^a, meshing with gear, 12^a, on the shaft, 13^a, extending through the tubular shaft, 13^b, and carrying the propeller, 14^a, at its outer end. The propellers are thus arranged to rotate 80 upon substantially the same axis in close proximity to each other, and as the engines are located in reverse positions, it will be noted from the gearing that the propellers are connected to turn in opposite directions, 85 as indicated by the arrows in Fig. 2.

Fig. 3 shows a similar construction with the addition of another engine, C, located at the rear of the other engines and having its crank shaft, 10^c, in the same axis with 95 the other propeller shafts. The crank shaft, 10^c, is coupled to a propeller shaft 13^c, which extends through the concentric hollow shafts, 13^a and 13^b, and carries the propeller, 14^c, the connections being such as to 100 rotate the adjacent propellers in opposite directions.

In Fig. 4, my improvement is shown applied in connection with two engines, A and B, of the ordinary eight-cylinder V type, located in tandem, and having their respective crank shafts, 10^a and 10^b, connected through the respective sets of gears, 11^a and 12^a, and

11^b and 12^b, with the propeller shafts, 13^a and 13^b, respectively. The tubular shaft, 13^b, may extend through the V shaped space between the cylinders of the engine, B, and 5 be rotatably mounted in the frame in any suitable manner, while the shaft, 13^a, is rotatably mounted within the shaft, 13^b, and may also be provided at its rear end with a bearing in the frame of the engine, A. 10 A flexible coupling, 16, may be inserted in the shaft, 13^a. As the engines are located back to back, and the gears of the respective engines are driven from the opposite ends of the crank shafts, the propeller shafts and 15 the corresponding propellers, 14^a and 14^b, will be rotated in opposite directions and entirely independently of each other.

The construction of Figs. 5 and 6, is similar to that of Figs. 1 and 2, except that the 20 two engines, A and B, instead of being of the vertical six-cylinder type, are of the V type mounted on the common crank case, 15, the connections otherwise being substantially the same as before described.

25 The modification shown in Figs. 7 and 8 is another tandem arrangement of the two engines, A and B, the same as shown in Fig. 4, except that the engines are of the radial multi-cylinder type, with fixed cylinders.

30 The propeller shafts, 13^a, and 13^b, are mounted in suitable bearings upon the frame between two adjacent cylinders, as indicated, and are driven in opposite directions by the respective pairs of gears, 11^a and 12^a, 35 and 11^b and 12^b, as before described.

Various other modifications as to the type of engines employed, and the form of the connections used, may be readily worked out, and all embodying the essential features of my invention comprising two or

40 more engines, each driving a separate propeller, the propellers being mounted on a common axis, in close proximity to each other, and rotating in opposite direction.

45 The tandem arrangement shown in Fig. 4 may be preferred for some reasons, since these standard V shaped engines may be purchased in the market, and be readily modified to install the propeller shafts; also 50 any desired number of engines may be readily connected up to the corresponding number of propellers, as it is simply a matter of providing the desired number of concentric hollow shafts for the same.

Having now described my invention, what I claim as new and desire to secure by Letters Patent is:

1. In an airplane, the combination of a plurality of engines, a hollow shaft mounted on the engine frame and having a driving gear at the rear thereof, a propeller fixed on the front end of said shaft, another shaft rotatably mounted within and extending through said hollow shaft, another propeller fixed on the front end of the inner shaft, a driving gear at the rear end of said inner shaft, and driving connections from the respective engines to said gears on the outer and inner shafts. 60

2. In an airplane, the combination of a plurality of engines, a hollow shaft mounted on the engine frame, a propeller fixed on the front end of said shaft, a driving gear fixed on the rear end of said shaft, another shaft rotatably mounted within and extending through said hollow shaft, another propeller fixed on the front end of the inner shaft, a driving gear at the rear end of the inner shaft, and independent driving connections between said engines and the respective driving gears on said shafts for rotating the same in opposite directions. 70

3. In an airplane, the combination of a plurality of engines arranged in tandem on the center line, a hollow shaft mounted on the forward engine frame, a propeller fixed on said shaft in front of said engine, another shaft rotatably mounted within said hollow shaft, another propeller mounted on the forward end of said inner shaft, and independent driving connections from said engines to the respective shafts at the rear of the forward engine. 80

4. In an airplane, the combination of a plurality of engines arranged in tandem on the center line, a hollow shaft mounted on the forward engine frame, a propeller fixed on said shaft in front of said engine, another shaft rotatably mounted within said hollow shaft, another propeller mounted on the forward end of said inner shaft, driving gears on said shafts at the rear of the forward engine, and independent driving connections from said engines to the respective driving gears on said shafts. 90

In testimony whereof I have hereunto set my hand.

BENJAMIN DOUGLAS THOMAS.
